UNITED STATES PATENT OFFICE.

FRED M. KILFOYLE, OF STORRS, UTAH.

CLOTHESPIN.

1,398,969.

Specification of Letters Patent. Patented Dec. 6, 1921.

Application filed May 20, 1920. Serial No. 382,811.

To all whom it may concern:

Be it known that I, FRED M. KILFOYLE, a citizen of the United States, and a resident of Storrs, in the county of Carbon and State 5 of Utah, have invented a certain new and Improved Clothespin, of which the following is a description, reference being had to the accompanying drawing, which forms a part of my specification.

- 10 My invention relates to a pin for hanging or securing clothes on a line; the invention having for its object the provision of a construction which will firmly grip the clothes and hold the same against accidental removal or displacement; while at the same 15 time providing a construction which will obviate the necessity of placing the clothes over the line as is the case with clothes pins as at present employed.
- 20 The invention contemplates a pin, of the character described, intended to be made from suitable non-rusting metal and formed so that the pin, with the attached clothes, may be snapped onto and suspended from 25 the line or wire; at the same time providing a construction which will in no way injure or tear the clothes.

The objects and advantages of my invention will be readily comprehended from the 30 following detailed description of the drawing, wherein:—

Figure 1 illustrates my improved pin in elevation.

Fig. 2 is a longitudinal sectional view 35 taken on the line 2—2 of Fig. 1, looking in the direction of the arrows; with the non-gripping condition of the pin shown in dotted lines.

Fig. 3 is a cross sectional view taken on 40 the line 3—3 of Fig. 1 looking in the direction of the arrows.

Fig. 4 is a detail view illustrating a modified form.

My improved clothes pin contemplates two 45 elements or members; each preferably composed of metal such as non-rusting spring wire and the specific embodiment of the invention as disclosed in the first three figures of the drawing, comprises a main portion 10 50 formed from a suitable length of wire bent at an intermediate point so as to provide the two parts or legs 11 and 12 arranged in spaced relation and substantially parallel with each other throughout a major portion 55 of its length as shown in Fig. 1. Each part or leg 11 and 12 at its upper or disconnected

part is looped or preferably coiled as shown at 13, in an outward direction, that is away from the adjacent part or leg and terminating in the free ends 14 which are disposed in a direction toward the opposite or closed end of the pin. The free ends 14 are also preferably provided with a double or ogee curve as shown at 15 in Fig. 2, and normally disposed at an inclination to the longitudinal axis of the pin.

Both parts or legs 11 and 12 at a point slightly in advance of the loops or coils 13, are shown provided with a slight bend in the direction away from the free ends 14, 70 as shown at 16 in Fig. 2. This bend 16 in conjunction with the curvature 15 in the ends 14 provides a pocket or space 17 adapted to receive the line or wire, see Fig. 2.

The opposite or closed end of the pin is 75 bent so as to provide the substantially parallel portions 18 and the laterally bowed and more widely separated portions 19. As can be seen in Fig. 1, the bowed portions 19 provide an enlarged opening or pocket which 80 constitutes the clothes-receiving and releasing portion of the pin, namely the point where the second or movable element of the pin accomplishes its gripping and releasing functions.

The second element or gripping member 20 of the pin, like the main member 10, is also preferably composed of non-rusting spring wire bent back into loop form, with the ends wound about the legs or parts 11 90 and 12 as indicated at 21: the turns or coils about the parts or legs being such as to permit member 20 to freely slide lengthwise of the main member or element 10 from a point adjacent the enlarged or laterally bent part 95 19 toward the opposite end of the main portion. The intermediate or loop end of gripping element or member 20 is bent substantially at right angles in a direction toward the main member 10 so as to provide the 100 gripping end or head 22. At the point where the element or member 20 is bent to form the head 22, the two strands of member 20 are bent toward each other so as to permit said restricted portion or neck to 105 pass through the lower end of element 10, intermediate of the substantially parallel portions 18 thereof while the head 22 is disposed therethrough and to the opposite side of the main element or member, as can more 110 clearly be seen in Fig. 2.

It is evident from this construction that

when the element or member 20 is at the lower end of the main element or member 10 as disclosed in Figs. 1 and 2, it will be in interlocking relation with the main element 10 or in clothes-gripping position, because the head portion 22 is of greater transverse dimensions than the distance intermediate of the substantially parallel portions 18 of the main member. In order therefore to release the head or gripping portion 22, it is necessary to move element or member 20 lengthwise of main member or element 10 until the head or gripping portion 22 reaches the opening provided by the bowed portions 19.

The ends of the wire which form the gripping element or movable part 20 are preferably bent toward each other and outwardly at right angles to both members so as to provide the thumb or finger-engaging portion 23, through the medium of which the element or member 20 may be manipulated and caused to slide lengthwise of the main element or member 10.

25 The main member 10, or rather both strands or legs 11 and 12 thereof, are preferably each provided with a slight bend in a direction away from the side on which member 20 is disposed, as shown at 24; this 30 bend 24 being at a distance from the laterally bent or bowed portions 19 and substantially corresponding with the length of the movable member 20, to enable the gripping end or head 22 to reach the enlarged opening 35 formed by the laterally bent portions 19, preferably slightly before the coiled part 21 of member 20 reaches the bend 24 of the main member or element 10. The purpose in providing the bend 24 in the main element or member 10 is to maintain the gripping element or movable member 20 in releasing and raised position or somewhat 40 separate relation with the member 10, as shown in dotted lines in Fig. 2.

45 In practice, the clothes are placed across the enlarged opening formed by the laterally bowed and widely separated portions 19; the movable member 20 is then forced lengthwise of the main member 10, its head 22, with 50 the clothes, forced through the opening just referred to and the member 20 slid toward the closed end of member 10, when the head or gripping portion 22 of member 20 with the clothes will be firmly gripped by the 55 lower substantially parallel portions 18; the clothes being securely held between the neck or restricted portion 25 of the movable member 20 and the substantially parallel portions 18 of the main element or member 60 10; the head 22, of course, preventing any separating or lateral movement of member 20 in a direction away from the main element or member 10 as long as the movable member or element 20 is in the position indicated in Fig. 1. It has been found in prac-

tice, that the clothes will not only be held in place by the movable element 20, but any downward pull on the clothes will induce a firmer gripping relation between the elements or members and thus prevent any 70 possibility of the clothes becoming detached.

With my invention, the pin may be properly secured to the clothes and the latter with the attached pins then taken to the place where the line is located at which time the 75 lower or clothes-gripping end of the pin may be grasped and its free ends 14 snapped onto the line or wire with slight downward pressure so as to force the line or wire to the point indicated at 17 in Fig. 2. With the 80 pin made of spring wire, it is evident that the free ends 14 will flex outwardly to permit the passage of the line or wire and at the same time provide a gripping relation therewith.

85 It is apparent that with my improved construction, the clothes will be suspended beneath the line or wire so that the clothes will be prevented from contacting with the line or wire and the possibility of becoming soiled by the line therefore eliminated. With my improved construction, the difficulty and labor encountered in hanging clothes on a wire located out in the open, especially during cold weather when the clothes are apt to 90 freeze on the wire or line, will be overcome and somewhat reduced and the necessity for long exposure on the part of the user obviated; while at the same time eliminating the necessity for constantly cleaning the line or 95 wire before the clothes are hung out for drying. In constructing my improved pins of non-rusting spring wire, they may, when necessary, be cleaned in hot water and thus prevent the clothes from becoming marred 100 or soiled at points where they are attached. Furthermore, my improved pin will enable the user to attach or suspend the clothes from a line or wire which is suspended or arranged at an elevation somewhat above the reach of 110 the user without the necessity of climbing, because in such instances, the lower attaching end of the pin may be grasped by the user and snapped over the wire or line arranged overhead.

115 Instead of providing the movable element or member 20 with the twists 21 disposed about the strands or legs of the main element 10, the movable member 20 may be formed from a flat strip of suitable metal, or 120 it may be provided with a flattened portion as at 26, see Fig. 4, bent into the angular or U-shaped formation shown, to provide the two parallelly disposed portions 27 and 28, provided with aligned apertures for the passage of the strands of legs 29 of the main element or member; the aligned apertures being of a size sufficient to permit the gripping member to have sliding relation with the main member or element.

While my improved pin may be made of any suitable material, I prefer, however, to construct the pin out of round metal or spring wire so as to present rounded surfaces to the clothes and thus prevent the possibility of injury to the clothes when the latter is wedged or gripped in the lower gripping end of the pin; the metal or wire at the same time possessing sufficient resiliency to enable a gripping relation being formed with the line or wire.

I have shown and described what I believe to be the simplest and best embodiments of my invention, but modifications may be made in certain details without, however, departing from the spirit of my invention.

What I claim and wish to secure by Letters Patent is:—

1. A clothes pin, comprising a main member composed of a single piece of non-rusting wire bent to provide two parallelly arranged strands or portions, with the ends of the strands or portions curled upon themselves to provide resiliency and terminating in downwardly presented portions disposed toward one side of a longitudinal axis of the main portion and normally tending to move toward a plane substantially parallel with the main portion, said downwardly presented portions constituting line gripping portions, while at the intermediate or closed end of the member the strands are disposed in parallel relation for a predetermined distance and then bent laterally in opposite directions to provide an enlarged space therebetween terminating in a restricted elongated gripping loop, and a second member composed of a single piece of wire bent into loop form to provide similarly disposed strands or portions whose ends are formed to slide on the strands of the main member above said enlarged space, the ends of the second member being bent to provide a finger-engaging portion while the intermediate closed end of the second member is bent at right angles to the main part thereof and
2. A clothes pin, comprising a main member composed of a single piece of wire bent to provide two parallelly arranged strands or portions, the ends whereof are curled upon themselves and terminate in downwardly presented portions disposed toward one side of the longitudinal axis of the main portion and normally tending to move toward a plane substantially parallel with said main portion to provide a line gripping portion, the strands at the intermediate or closed end of the member, for a short predetermined distance, being disposed in parallel relation and then bent laterally in opposite directions to provide an enlarged space therebetween, terminating in an elongated gripping loop, the strands of the first member at a point intermediate of said enlarged space and the line gripping portions thereof being bent toward one side of the longitudinal axis of the member, opposite to the side of the line gripping ends, and a second member composed of a single piece of wire bent into loop form to provide parallelly disposed strands or portions whose ends are coiled about the strands of the main member at a point above said enlarged space, to permit the second member to slide lengthwise of the first member onto the last mentioned bent part thereof whereby the free end of the second member is caused to move away from the first member, the intermediate or closed end of the second member being bent at right angles thereto and adapted to be disposed through the elongated gripping loop of the first member.
